UNITED STATES PATENT OFFICE

95,340

DESIGN FOR A DART GAME TARGET

Arthur S. Hanlyn, Seattle, Wash.

Application February 13, 1934, Serial No. 50,713

Term of patent 3½ years

To all whom it may concern:

Be it known that I, Arthur S. Hanlyn, a citizen of the United States, residing at Seattle, in the county of King and State of Washington, have invented a new, original, and ornamental Design for a Dart Game Target, of which the following is a specification, reference being had to the accompanying drawing, forming part thereof.

The figure is a perspective view of a dart game target, showing my new design.

I claim:

The ornamental design for a dart game target, as shown.

ARTHUR S. HANLYN.
